HERBERT K. SMITH, OF JAMAICA, NEW YORK, ASSIGNOR TO ABBOTT COIN COUNTER COMPANY, OF WILMINGTON, DELAWARE, A CORPORATION OF DELAWARE.

COIN-COUNTING MACHINE.

1,080,381.

Specification of Letters Patent.

Patented Dec. 2, 1913.

Application filed February 18, 1913. Serial No. 749,197.

To all whom it may concern:

Be it known that I, HERBERT K. SMITH, of Jamaica, in the county of Queens and State of New York, have invented certain 5 new and useful Improvements in Coin-Counting Machines, of which the following is a specification.

Under my invention the coins to be counted are placed in a container having a 10 bottom consisting of a rapidly revolving disk on which the coins rest, and through the agency of which they are discharged singly by centrifugal action through a suitable peripheral outlet or gate in the walls 15 of the container. With this centrifugal coin-discharging container I combine a rotary carrier wheel whose peripheral speed is slightly greater than that of the rotary disk, and which is so located with reference to 20 the point of centrifugal discharge from the container as to take hold of the coin before it leaves the centrifugally acting disk, and, by reason of its relatively greater peripheral speed, takes off and carries away the coin 25 from the disk, keeping it well in advance of the coins in rear, and passing it through the counting portion of the machine, and thence to the stacker tube, bag, or other receptacle for the counted coins. This combination with the centrifugally discharging 30 container, of a carrier wheel which takes hold of the coin before it leaves the centrifugal bottom of the container, and carries it along with accelerated speed; is, I believe, 35 new with me. By taking the coin with the carrier wheel directly from the centrifugal bottom, the danger of clogging by reason of coins jamming in the runway through which they pass after leaving the container, is very 40 much lessened, and, in conjunction with the more rapid peripheral movement of the carrier wheel, and consequent accelerated speed of the coin, effectually prevents the overlapping of a coin by a following coin, each 45 coin taken by the more rapidly moving carrier wheel being, by its more rapid movement, at once separated from the coin next behind which has not yet reached the carrier wheel.

50 Another portion of my improvements relates to the coin counting devices, the object being to provide a mechanism which is effi-

cient, accurate, and easily operated, and can be readily and quickly adjusted for either "packaging" or "bagging" coin. "Packaging" refers to the delivery of coin in stacks of determinate number, say 25, 50, 75, etc., as the case may be. "Bagging" refers to the delivery into a bag or other receptacle of coin in a continuous stream, in 60 larger numbers, say 500, 1000, or more. In my machine, with slight and readily made change of adjustment, I can deliver the coin in stacks of multiples of any given number—say 5—from 25 to 200; or I can, with 65 other slight changes in adjustment, adapt it for "bagging" purposes, the count of the coin being taken on the well known Veeder counting register, or other suitable register.

A machine thus organized is efficient, and 70 can be operated at great speed without danger from clogging or other interference with its proper working.

To enable those skilled in the art to understand and use my invention, I will now proceed to describe more particularly the manner in which the same is or may be carried into effect in connection with the accompanying drawings, forming part of this 75 specification, in which—

Figure 1 is a plan of the machine, with the front portion of the coin bin broken away. Fig. 2 is a front elevation of the same. Fig. 3 is a bottom plan of a portion of the same sufficient to show the driving gearing and 85 belting. Fig. 4 is a much enlarged section of the counting mechanism on line 4—4 Fig. 6. Fig. 5 is an inner face elevation of the bearing for the wheel end of the shaft that drives the carrier wheel. Fig. 6 is an enlarged plan of a portion of the machine, with the top plate which covers the counting devices removed. Figs. 7 and 8 represent the setting disk in plan and side elevation respectively. Figs. 9 and 10 are corresponding views of the lower counting wheel, or ratchet wheel. Fig. 11 is a sectional view in perspective of such parts as are needed to illustrate the coacting relations of the centrifugal container and the carrier wheel. 100 Fig. 12 is a sectional elevation on line 12—12 Fig. 6, designed to illustrate more clearly the devices for adjusting the dimensions of the gate through which the coins pass one

by one from the centrifugal container to the carrier wheel, Fig. 13 is a vertical section lengthwise of the runway through which the coins pass from the centrifugal container to the carrier wheel and thence to the discharge or delivery point. Fig. 14 is a sectional elevation on line 14-14 Fig. 6. Figs. 15-23 inclusive are detail views of various parts of the mechanism which 10 will be hereinafter more particularly referred to.

In the drawings A is a suitable table or stand for supporting the working parts of the machine.

15 B is the bin holding the supply of coins to be counted. It is elevated on supports above the level of the centrifugal container, and its open mouth overhangs the container, as seen in Figs. 1 and 2. The coins are fed to 20 the container from this bin by hand.

The container consists of a cylindrical shell C, closed at its lower end and firmly attached to the top of the table or frame A, as shown more clearly in section in Fig. 11; 25 and a rotary disk D, mounted axially within the container, and constituting the bottom of the same. The periphery of the disk runs in close proximity to the cylindrical wall of the container, and the disk itself is rigidly 30 mounted on a vertical shaft d, mounted in ball bearings d', carried by the shell C, as shown in Figs. 1 and 11, and having on its lower end a pulley d² (Figs. 2, 3), by which it is driven from the main shaft 1, by a system of belting and pulleys 2; 3, 4, as indicated clearly in the figures just referred to. The main shaft, 1, may be driven from any suitable source of power. In the drawing it is supposed to be revolved by hand, and is 40 for this purpose provided with a crank handle 5. This system of pulleys and belting is of course typical of any suitable gearing for transmitting motion to the disk D of the centrifugal container from the prime mover.

In the vertical wall of the container C there is an opening at one point to provide an outlet for the coins carried out peripherally against the wall of the container by the 50 centrifugal action of the rapidly revolving disk D with which they travel, as shown in Fig. 11. From this figure, as also in Fig. 13, all parts are omitted save such as will illustrate the coactive relations of the centrifugal 55 container and the carrier wheel E. It is sufficient to say here that the carrier wheel is arranged in a runway leading from this opening in the wall of the container, to contact with the floor f of this runway (preferably made of sheet steel) which floor meets the periphery of disk D, and is flush with the face of the same, so that coins will pass smoothly from the disk onto the floor f. The carrier wheel revolves at slightly 60 greater peripheral speed than the disk D,

and it is so located with reference to the latter that it takes hold of the nearest coin x before the latter leaves the disk, as shown plainly in Fig. 13, and by its relatively accelerated speed, draws this coin away from 70 the next following one, and with rapid movement projects it forward through the runway to the discharge opening at the end of the same, as shown at x' Fig. 13. An inclined fender g is provided at this point to 75 direct the coin x' into the opening f². A light leaf spring h projects through the stationary wall f' of the runway (Fig. 11) and rests upon the disk back of the wheel E. The coins pass one by one between this leaf 80 spring h and the disk in their passage to the carrier wheel. The spring prevents the coins from overlapping one another and assures them in proper position. The coins at the periphery of the disk, before they reach the leaf spring h, pass through a gate of dimensions to admit one coin only at a time. This gate which is adjustable both as to width and height, so as to conform to the thickness and diameter of the coins of the particular denomination acted on, is not shown in the two figures referred to (excepting a part of it in Fig. 11, just enough to show how the coins pass between its lower edge and the face of the disk) and will be 85 presently described.

The carrier wheel E is provided with a rim or tire e of soft rubber or other elastic and yielding material into which the coin will embed itself, so as to assure that it will 100 be taken and carried along by the wheel. The carrier wheel E is fast on a shaft e' (see more particularly Figs. 1, 2, 3) supported in proper end bearings and driven from the main shaft 1 by a counter shaft 6, 105 taking motion from the main shaft through beveled gears 7, 8, and provided with pulley 9, from which passes belt 10 to a pulley 11 on the carrier wheel shaft. This motion transmitting mechanism is so proportioned to that for driving the centrifugal disk D as to impart to the former the accelerated speed 110 over the latter hereinbefore provided for.

It is desirable that the carrier wheel should be held with spring yielding pressure 115 against the bottom plate f of the runway, so that it may be capable of rising and falling bodily to such an extent as to accommodate itself to variations in the thickness of the coins passing beneath it. To this end the 120 end of the carrier wheel shaft nearest the runway is supported in an open bearing i (Fig. 5) in which it can rise and fall, said bearing being formed in an arm i' pivoted at one end to a supporting stand I at i², and held in position at the other end by a slot and set-screw connection i³ which will permit the adjustment of the bracket bearing arm i', and the securing of the same in adjusted position. The set-screw of this ad- 125 130.

justment is shown more plainly at ⁵ Fig. 2. The other end of the carrier wheel shaft is mounted in a bearing ⁶ swiveled on a horizontal axis in a supporting stand or bracket ⁵ ⁶, so that the carrier shaft at its wheel end may rise and fall in the bearing ⁶. This free end of the shaft is held down with spring yielding pressure by any suitable means—in this instance by the belt 10, which is ¹⁰ formed of a spring wire close coiled in tubular form, and slightly stretched between the pulleys 9, 10, around which it passes so as to be under tension. The pulley 11 on the carrier wheel shaft is between the two bearings which support the ends of the shaft, ¹⁵ and thus exerts upon the shaft yielding pressure in a direction to hold it down in its open bearing ⁶.

I pass now to a description of the gate ²⁰ through which the coins pass one by one from the centrifugal container. The gate is formed primarily of the metal strip K which spans the opening in the wall of the container C, as seen more particularly in Figs. ²⁵ 1 and 6. Its central limb k is parallel with the stationary side f' of the runway, and forms the other side of said runway for a portion of the length of the latter, an extension k' on the part k forming the rest of ³⁰ this side of the runway. The end limbs k², k³, of the strip are bent at an angle to the center limb k, but parallel to one another. The end limb k² extends through a slot formed in the walls of the container on the ³⁵ far side of the opening therein. The opposite end limb k³ is secured to the exterior of the wall of the container at the near side of the opening by a set-screw k⁴, which passes through a longitudinal slot k⁵ in the part k³ ⁴⁰ into the container wall, as shown more particularly in Fig. 2. To the end of the limb k³ is secured rigidly a screw k⁶, which engages a nut k⁷ swiveled to turn in a bracket k⁸, attached to the container wall, as illustrated in Figs. 1, 2, and 6. By means of the adjusting screw k⁶, the strip K can be adjusted lengthwise bodily, and can be secured in its adjusted position by the set screw k⁴. A pull on the strip K, by reason of the incline on which the limbs k², k³, work, will cause the central portion k, k' to move away from, but still parallel to, the opposite stationary side f' of the runway, thus widening the runway. On the other hand, a movement ⁵⁵ of the strip K in the opposite direction will cause the central limb k, k' to approach the other side f', thus narrowing the runway. In this manner the width of the runway can be adjusted to conform to the diameter of ⁶⁰ the coins operated on. The limb k² of the strip K is cut away along its lower edge so as to be some distance above the face of the centrifugal disk C, thus leaving between k² and the disk a space which forms a slot s ⁶⁵ (Figs. 12, 14) through which the coins can

pass from the interior of the centrifugal container, the wall of the container at the point where the limb k² passes through it bounding the slot at that end. Under this construction, it will be seen that a lengthwise movement of the strip K in one direction will lengthen the slot, and in the other direction will shorten it, the length of the slot varying directly with the width of the runway. In this way, at one operation, the adjustment of these two parts can be effected. ⁷⁰

On the container wall opposite a pointer k⁹ on the strip K (see Fig. 2) is a properly graduated scale k¹⁰, by which the strip K can be readily adjusted for different diameters of coins—cents, ten cent pieces, nickels, quarters, etc. It is desirable that the uncut portion of the lower edge of the strip K should be held as closely as possible in proximity to the face of the rotary disk D without absolute contact therewith. To provide an efficient means of securing this adjustment I support the strip K at its two ends on rather stiff plate springs k¹¹ which hold up the strip; and above the ends of the strip, opposite to points below where the plate springs are located, I provide set-screws k¹² carried by brackets attached to the outside of the container wall, and bearing down upon the upper edge of the strip. By means ⁸⁵ of these set-screws the strip K can be depressed against the stress of the springs k¹¹, so as to adjust its lower edge to a nicety with reference to the face of the disk D beneath. ⁹⁰

Means for varying the width of the slot to ¹⁰⁰ accord with the varying thickness of the coins operated on should also be provided, inasmuch as it is essential that the width of the slot should not be greater than to comfortably accommodate a single coin of a ¹⁰⁵ given thickness. To this end I make use of the device shown generally in Figs. 1 and 6, and more in detail in Figs. 12 and 14. I erect upon the limb k² a vertical support l on the inner face of which is mounted a ¹¹⁰ plate l' held to the support by slot and set-screw connection l'' which will permit the vertical adjustment of this plate. An adjusting screw l³ swiveled in an overhang on the top of plate l' and engaging an internally screw-threaded nut or tubular lug l⁴ on the back of support l is used to effect the adjustment of the plate. Upon the lower portion of the plate l' is firmly secured the gate strip l'', which moves up and down with ¹¹⁵ the plate, and which is of sufficient length for the largest coin to be taken care of by the machine. The lower edge of this gate strip determines the width of the slot. And the working width of the slot s will be determined by the position of the gate strip, as will be understood without further explanation. To secure accurate adjustment of the gate there may be on the vertically adjustable plate l' a graduated scale l⁵ (Fig. ¹²⁰ 130

14) from 10 cents to one dollar, and on the stationary support *l*, a pointer *l'*. By adjusting the plate *l'* to bring any one of the graduations on the scale opposite to the pointer *l'*, the width of the slot *s* will be adjusted to the thickness of the coin to which that graduation is appropriate.

The fender *g*, hereinbefore referred to in connection with Fig. 13, is shown detached in Fig. 15; and appears in plan in Fig. 6 in connection with the parts with which it is associated. It is held in the inclined position indicated in Fig. 13 by guides *g'* in which it can slide lengthwise, and it extends through a slot in the stationary wall *f'* of the runway into the runway, with its head bearing against the opposite and adjustable wall *k'* of the runway, against which it is held with yielding pressure by a spring *g''* which bears against its outer end, as seen in Fig. 6. Under this arrangement it will be seen that the fender will adapt itself to the movement of the adjustable wall of the runway to and from the stationary wall thereof.

To prevent the coins in the centrifugal container from gathering in undue number at the gate through which they are discharged one by one, I make use of a deflector *m*, shown in Figs. 1 and 12. This deflector is secured by its base to the inner face of the container wall in a position to divert from the discharge gate the mass of coins carried around on the rapidly revolving disk-bottom *D* of the centrifugal container, and at the same time its lower edge is elevated at such a distance above said disk as to permit the passage under it of sufficient coins to supply the gate as indicated in Fig. 12, where the coins are represented in dotted lines. The deflector *m* is vertically adjustable by means of a slot and set-screw connection *m'* with the container wall; and is assured in vertical position in its movement of adjustment by a vertical tongue and groove sliding connection with the wall of the container, indicated at *m''* Figs. 1 and 12. The rotary disk *D* of the centrifugal container has at its center a conical projection *d* (Fig. 11) which prevents any coins from gathering on the dead center of the disk when the latter is in revolution.

Y is a stacker tube of any convenient or usual type, to receive the coins discharged from the opening *f''* at the end of the runway (Figs. 2, 3, 13).

It remains to describe the coin counting mechanism, which is contained and housed between the top and bottom plates *f³*, *f⁴*, the latter of which is substantially flush with the floor *f* of the runway. The principal parts of this mechanism are the star wheel *n*, the teeth of which, as seen in Fig. 6, project through a slot in the wall *f'* into the runway in position to be struck by the pass-

ing coins, as usual in this class of counting devices; the ratchet wheel *o*, which is the counting wheel, and which derives its movement from the star wheel; the pawl lever *p* for holding the ratchet wheel against back movement as it is advanced tooth by tooth by the star wheel; and the setting disk *r* for controlling and determining the extent of rotary movement of the ratchet wheel. The setting disk is shown in plan and elevation in Figs. 7 and 8; the ratchet wheel is similarly shown in Figs. 9 and 10. The dotted lines *f³* in Fig. 8 indicate the top plate *f³*, and the dotted lines *f⁴* in Fig. 10 indicate the bottom plate *f⁴*. The manner in which I prefer to assemble the star wheel *n*, ratchet wheel *o* and setting disk *r*, between the top and bottom plates *f³*, *f⁴*, is illustrated clearly in Fig. 4. The setting disk and ratchet wheel are assembled and mounted upon a vertical screw-threaded spindle *V* which passes from below up through the two plates *f³*, *f⁴* and has on its end above the top plate *f³* a nut *v'*. In putting the parts together, the top plate *f³* is removed. The screw-threaded spindle *V* is inserted from below until its head brings up against the bottom of plate *f⁴*; the internally screw-threaded block *v* is screwed on the spindle down upon the top of the lower plate *f⁴*. Then there are screwed successively upon the spindle *V* the cylindrical block *v'* which serves as a hub on which the ratchet wheel *o* is fitted and can revolve; the spacing block *v²*; and the cylindrical block *v³* which serves as a hub on which the setting disk *r* is fitted and can rotate. The top plate *f³* is then put on and the nut *v'* is screwed down on the plate to clamp it upon the flanged head of the block *v³* beneath. Slightly dished metallic washers are interposed between the parts as indicated at *v⁴*. Between the setting disk and the ratchet wheel is a helical spring *t* which is secured at its outer end to an anchor pin *t'* on the face of the ratchet wheel, and at its inner end to the spacing block *v²*. This spring tends to revolve the ratchet wheel in the opposite direction from that in which it is revolved by the star wheel *n*. The star wheel *n* (see Fig. 4) is fast on, or made in one with, a shaft *n'*, and the reduced end of said shaft below the star wheel is fashioned as a journal to fit in a bushing *n²* secured in a hole in the bottom plate *f⁴*, forming a stepped bearing for the star wheel shaft. On the externally screw-threaded end of the bushing, beneath the plate *f⁴*, is screwed a cap *n³* to be filled with a lubricant such as oil, which will in effect form an oil bath for the bearing. The star wheel shaft extends up vertically through a bearing in the top plate *f³*; and between a shoulder *n⁴* on it, and the under side of the top plate, is confined a coiled spring *n⁵* which tends to 130

hold the shaft down in its stepped bearing, so that the star wheel shall at all times be held closely down against, or in close proximity to, the plate f^4 . On the upper portion 5 of the shaft is a small beveled gear n^8 (Fig. 5) which meshes with a beveled wheel n^7 on the main shaft of a counting register n^8 (Fig. 1) of the well known Veedor type, or other suitable type, registering for each 10 pulse of the star wheel due to the passage of one coin, and consequently indicating the total number of coins which may have passed through the machine.

Motive power for the ratchet wheel o in 15 the counting direction is furnished by a vertical pin n^9 on the face of the star wheel, the length of which is sufficient to enable it to engage the teeth in the ratchet wheel o as seen in Fig. 4. The pin n^9 is so located 20 with reference to the ratchet wheel as to engage the same during each revolution long enough to advance it one tooth. As the star wheel has five teeth, and is caused to make one complete revolution by five coins, each 25 of which in its passage through the runway causes the star wheel to make one fifth of a revolution, it follows that each tooth on the ratchet wheel represents five coins. The ratchet wheel thus counts in multiples of 30 five—one tooth representing five coins, two teeth ten coins, three teeth fifteen coins, and so on.

The setting disk r has the same dimensions as the ratchet wheel, and is provided 35 with teeth of like shape and size as those of the ratchet wheel, the teeth of the disk above registering with the teeth of the wheel below. The teeth of the setting disk are intended merely to engage a screw locking 40 pin r' (see Fig. 1 and also Fig. 21 which is a section on line 21—21 Fig. 1), which, after the setting disk has been rotated to the desired position of adjustment, is screwed down into the interval between the 45 two disk teeth directly below, to hold the disk rigidly in that adjusted position. The disk teeth have the same individual value—viz: five coins—as the ratchet teeth; and as a matter of convenience, I divide the teeth 50 on the disk into successive groups of five, distinguished on the margin of the disk by the number of coins the groups of five, as they recede from the zero point, represent—25, 50, 75, etc., as seen in Fig. 7.

In the top plate f^3 is a segmental slot r^2 , through which the designating numbers on the setting disk will be successively exposed as said disk is rotated; and on one border of the slot is a pointer r^8 . A portion of 60 the toothed periphery of the setting disk r projects beyond the outer edge of the top plate f^3 , as seen in Fig. 1, and by this exposed portion the disk may be manipulated to bring any desired number, or other designation, on it opposite to the pointer r^8 . The

disk is then locked in this position by the screw locking pin r' , as before explained.

On the under face of the setting disk, and at, or near, the zero point, there is a dog r^4 , Figs. 7 and 8, for a purpose hereinafter indicated. The pointer r^8 (Fig. 1) is slightly depressed or bent downward; and there are two teeth r^6 and r^8 in the setting disk which are bent upward to lie in the path of the pointer. The one, r^6 , is located 75 at the zero point (Fig. 7) and, by bringing up against the pointer, prevents further revolution of the disk to the left beyond that point. The other one, r^8 , is located at the point marked "Bag" (Fig. 7) and prevents further rotation of the disk to the right beyond that point. The word "Bag" there indicates the point on the disk which should be brought opposite to the pointer r^8 when the machine is to be run for "bagging" 80 purposes—that is to say, when the coin is to be run through it in a continuous stream.

The pawl lever p is shown separately in sectional elevation in Fig. 22, and in plan, in its relations to the ratchet wheel and star wheel in Figs. 18, 19, 20. It is mounted on plate f^4 on a pivot p' on which it can oscillate. It has on its pawl end a tooth p^2 to engage the ratchet wheel, the pawl lever being spring pressed by a spring p^3 in a 95 direction to carry the pawl tooth toward the teeth of the ratchet wheel. The tooth p^2 is fashioned in any suitable or usual form which will permit the ratchet wheel to revolve in the direction of the arrow, Fig. 6, 100 but will hold it from revolution in the other direction; and to this end it has a flat face and rounded back, as seen in Figs. 6, 18, 19, 20. The opposite end of the pawl lever is fashioned in a handle p^4 by which the lever 105 may be manipulated against the stress of its spring to carry and hold it out of engagement with the ratchet wheel.

On the upper face of the ratchet wheel is a dog o' (Figs. 9, 10) which is designed to 110 engage the dog r^4 on the setting disk. When the ratchet wheel, by the handle p^4 , is released from the control of its pawl, its spring t will revolve it backward or to the left, and the dog o' , by bringing up against 115 the dog r^4 limits the extent of this movement. About diametrically opposite the dog o' there is a recess o^2 in the periphery of the ratchet wheel, of greater depth than the teeth of the ratchet, the front wall o^3 120 of this recess being indeed diametrically opposite the face of the dog o' which brings up against the dog r^4 in the setting disk. On the pawl lever is a stop arm p^5 , the end 125 of which, by this movement of the lever, has been carried into the path of a stop n^{10} on the star wheel, which stop brings up squarely against the end of stop arm p^5 , as shown in Fig. 18. This stop device arrests 130 further movement of the star wheel, and

consequently further passage of the coins, and serves to take off from the gearing that derives its movement from the star wheel the shock to which it otherwise would be subjected.

In operating the mechanism as thus far described, the setting disk r is so placed that the zero mark on it is opposite the pointer r^3 , the ratchet wheel o below it will stand with its dog o' against the dog r^4 on the setting disk, and the recess o^2 in the ratchet wheel will be so located that the pawl tooth will have dropped into the recess o^2 with its flat front face against the front wall o^3 of the recess, as indicated in Fig. 18, thus locking the ratchet wheel against any back movement. The parts having thus been brought to zero, the next step—assuming the machine is to be used for packaging coins—is to turn the setting disk r to the right to bring the desired number of its face opposite the pointer r^3 ; this movement, of course, carries away the dog r^4 on the disk from the dog o' on the ratchet wheel, but the latter is nevertheless held from following the setting disk by reason of the pawl. If it be supposed that the coins are to be counted in packages of 100, the setting disk is turned to bring the 100 mark on it under the pointer r^3 , and is locked tight in that position. The pawl is then manipulated to disengage it from the ratchet wheel, and the latter on its release, is at once thrown around by its spring t until its dog o' brings up once more against the dog r^4 on the setting disk. In this partial movement of backward revolution, it will have traveled a distance of about 20 teeth, each tooth representing 5 coins. The pawl is then released and allowed to drop back into engagement with the ratchet teeth which by this movement of the ratchet wheel have been brought opposite to it. The counting mechanism is thus "set" for 100 coins. The machine is then set in motion, the runway in which the carrier wheel revolves and the gate of the centrifugal container having been previously adjusted to the particular denomination of coins to be packaged. By the action of the rapidly revolving disk of the centrifugal container, the coins are ejected one by one through the gate, and are then taken by the carrier wheel and conveyed through the runway, striking the teeth of the star wheel in their passage and rotating it as hereinbefore explained. Each revolution of the star wheel advances the ratchet wheel one tooth, as indicated in Fig. 19, where the operating pin n^9 on the star wheel is represented as having engaged and being about to leave the ratchet wheel, and the pawl tooth is represented as having been lifted out of engagement with the ratchet tooth in front, and about to drop into engagement with the tooth in rear, on the

point of which it appears as resting. By the time the ratchet wheel has traveled a distance of 20 teeth, the recess o^2 will have been brought to a point where the pawl will drop into it, the stop arm p^8 by this movement of the pawl having been brought into position where the stop n^{10} on the star wheel will bring up squarely against it as before explained. Owing to the very rapid rate of revolution of the star wheel when in operation, I prefer to so construct and adjust the parts that the pawl will drop into the recess some little time before the stop n^{10} on the star wheel reaches the stop arm, so that the latter shall be surely in position to meet, and resist the impact of, the stop. With the same end in view, as well as to prevent the star wheel at any time from overrunning and to insure the proper presentation of each of its teeth to the coins, I make use of a retaining device which acts somewhat in the nature of a damper on the star wheel. This device, which is shown in plan in Figs. 16, 17, and in sectional side elevation in Fig. 23, is supported on the lower plate f^4 , as indicated in Fig. 23, and is located in convenient proximity to the star wheel. It comprises a lever w pivoted at w' between its ends to the plate f^4 ; and having an inclined elongated foot w^2 which is adapted to bear flatwise upon the backs of the star wheel teeth as they successively meet it, as indicated in Fig. 16, said lever being spring pressed by a spring w^3 in a direction to cause its foot to bear firmly upon the back of the tooth. As the star wheel revolves, the retaining or damper lever, as indicated in Fig. 17, rides over the back and point of the tooth on the back of which it has rested, until, as that tooth quits it, it drops and brings its foot forcibly and squarely upon the back of the next tooth, thus holding the star wheel down to its work and preventing any overrunning. The shorter arm of the pivoted damper lever which engages the spring w^3 is provided at its end with a lip w^4 which overlaps the end of the spring that meets it, and prevents any disengagement of the one from the other.

When the star wheel stops, the carrier wheel should stop also, in order not to urge along the coins beneath and in advance of it, against the locked star wheel. The momentum however is such that the carrier wheel may be actuated a short time even after power is turned off. To obviate this I use the tubular coiled spring belt hereinbefore referred to. This belt, when resistance by the stopped line of coins to further revolution of the carrier wheel is encountered, will slip on the carrier wheel shaft pulley around which it passes, thus checking rotation of the shaft and consequently of the carrier wheel. The 100 coins thus counted

drop into the stacker tube and are removed therefrom to be packaged in any usual or suitable manner. The pawl lever is then operated to release the ratchet wheel which at once returns to the position from which it started; the pawl lever is released and allowed to drop back into engagement with the ratchet wheel, and the machine is again in condition to count another 100 coin package.

When it is desired to use the machine for "bagging" coins, the setting disk is turned until the "bag" mark on it is brought opposite to the pointer n^s , and is then locked in that position. On releasing the ratchet wheel from control of its pawl, and allowing its back revolution, by the time it brings up against the dog n^4 , the recess o^2 in it will occupy the position shown in Fig. 20, in which it will be held by the pawl which engages the ratchet teeth in rear of the recess o^2 ; and its relations to the star wheel n are such that when it is in this position, the pin n^9 on the rotating star wheel will move through that recess without engaging or contacting with the ratchet teeth. The stop n^{10} on the star wheel, as indicated in Fig. 4, is below the level of the ratchet wheel and will not interfere with it in any position. The ratchet wheel will thus remain at rest, and the star wheel can revolve indefinitely so long as coins are fed to it. Under these conditions, the only counting done is by the Veeder register n^s which, as before explained, is actuated from the star wheel shaft by beveled gearing n^6 n^7 , as indicated in Figs. 1 and 5. In this use of the machine, the stacker tube is removed, and in its place is hung a bag to receive the coins. Assuming that the number of coins to be "bagged" is 1000, the operator first makes memorandum of the figures shown on the dial of the register n^s , and then starts the machine and runs the coins through it until the figures on the dial are 1000 in excess of those on his memorandum. The machine is then stopped and the bag containing the 1000 coins is removed and tied up. Whenever on the conclusion of the count, the end one of the figures on the dial of the register is 5, or 0 (as in the present instance it is shown to be on the dial of the register in Fig. 1), the star wheel pin n^9 is in a position in which it will not interfere with the teeth of the ratchet wheel, which, on being released from its pawl, can return at once to its normal position with reference to the setting disk. But in some cases the count may be arrested at a time when the end figure on the register dial is some figure other than 5 or 0. In this instance it becomes necessary to operate the register until one of these two numbers appears. To this end, as indicated in Fig. 5, I prolong the star wheel shaft n' to pass upward through a bearing on the stand

which supports the carrier wheel shaft at one end; and I provide it at its top with a milled head n^{11} by which it may be rotated to operate the register n^s until the concluding figure on the dial is either 5 or 0. This will bring the star wheel into a position where the pin n^9 is out of the way of the ratchet wheel; and the counting mechanism is thus cleared for the return of the ratchet wheel to its initial position.

Having described my invention and the best way now known to me of carrying the same into practical effect, I state in conclusion that I do not limit myself to the structural details herein shown and described in illustration of my invention, since manifestly the same can be considerably varied without departure from the spirit of the invention; but

What I claim herein as new and desire to secure by Letters Patent, is as follows:

1. In a coin counting machine, the combination of a centrifugal coin container comprising a stationary shell and a rotary bottom, with an opening in the wall of the shell to expose the rotary bottom; a gate spanning said opening in the wall of the container so as to leave exposed a peripheral segment of the rotary bottom to receive the coins which pass one by one through the gate from the interior of the container; a runway having a floor which meets and is flush with the exposed segment of the rotary bottom to receive the coins discharged therefrom; and a rotary carrier wheel located in the runway in close proximity to the centrifugal coin container to contact with and take hold of each coin before it passes entirely beyond the rotary bottom of said container, substantially as and for the purpose hereinbefore set forth.

2. In a coin counting machine, the combination of a centrifugal coin container comprising a stationary shell, and a rotary bottom, with an opening in the wall of the shell to expose the rotary bottom; a gate spanning said opening in the wall of the container so as to leave exposed a peripheral segment of the rotary bottom to receive the coins which pass one by one through the gate from the interior of the container; a runway, the floor of which meets and is flush with the exposed segment of the rotary bottom, and receives the coins discharged therefrom; a rotary carrier wheel located in the runway in close proximity to the peripheral segment of said rotary bottom to contact with and take hold of each coin before it passes entirely beyond the rotary bottom; and a spring presser located between the carrier wheel and the gate, to bear with yielding pressure upon the rotary bottom, between which presser and the rotary bottom the coins as they pass beyond the gate are received and carried along substantially

as and for the purposes hereinbefore set forth.

3. In a coin counting machine, the combination with a centrifugal coin container comprising a stationary shell and a rotary bottom with an opening in the wall of the shell to expose the rotary bottom; a gate spanning said opening in the wall of the container so as to leave exposed a peripheral 10 segment of the rotary bottom; a runway, the floor of which meets and is flush with the exposed segment of the rotary bottom, and receives the coin discharged therefrom; a rotary carrier wheel located in the runway 15 in close proximity to the centrifugal coin container to contact with and take hold of each coin before it passes entirely beyond the rotary bottom of said container; and actuating mechanism for said rotary carrier wheel 20 and rotary bottom, whereby the rotary carrier wheel is driven at a peripheral speed higher than that of the rotary bottom, substantially as and for the purposes hereinbefore set forth.

4. The centrifugal coin container comprising a stationary shell and a rotary bottom, with an opening in the wall of the shell to expose the rotary bottom, and the runway for the passage of coins discharged by centrifugal action from said rotary bottom, in combination with the strip K, spanning the opening in said wall, and consisting of a central limb k k' forming one side of the runway, and end limbs k² k³ inclined to the central limb in planes parallel to one another, the limb k² extending through a guide in the wall of the container, and having its lower edge cut away to form, in conjunction with the rotary bottom beneath, a slot s 25 through which the coin will be discharged by centrifugal action, the wall of the container forming the outer boundary of said slot; and means for bodily moving the strip K lengthwise in the plane of inclination of the limbs k² k³ and locking it in desired position, whereby at one operation the length of the slot s and the width of the runway may be adjusted to conform to the diameter of the particular denomination of 30 coins to be passed through the machine, substantially as and for the purposes hereinbefore set forth.

5. In a coin counting machine, a centrifugal coin container comprising a stationary shell and a rotary bottom, with an opening in the wall of the shell to expose the rotary bottom, and the runway for the passage of coins discharged by centrifugal action from said rotary bottom, in combination 35 with the strip K, spanning the opening in said wall, and consisting of a central limb k k' forming one side of the runway and end limbs k² k³ inclined to the central limb in planes parallel to one another, the limb k² 40 extending through a guide in the wall of the

container and having its lower edge cut away to form, in conjunction with the rotary bottom beneath, a slot s through which the coin will be discharged by centrifugal action, the wall of the container forming the outer boundary of said slot; means for moving the strip K lengthwise in the plane of inclination of the limbs k² k³ and locking it in desired position, whereby at one operation the length of the slot s and the width of the 45 runway may be adjusted to conform to the diameter of the particular denomination of coins to be passed through the machine; and a gate strip l⁵ mounted on the limb k² and vertically adjustable thereon to vary the 50 width of the slot s to conform to the thickness of the coin to pass therethrough, and means for securing said gate strip in its adjusted position.

6. In combination with the centrifugal container and the strip K spanning the opening in the stationary wall in said container and having in its lower edge the slot s through which the coins are discharged from said container, spring supports for 55 said strip, and adjusting screws mounted on the container and adapted to bear on the strip from above, to depress it against the yielding resistance of the spring supports, whereby the bottom edge of said strip may 60 be adjusted accurately with reference to the rotary bottom of the container, substantially as and for the purposes hereinbefore set forth.

7. The combination with the runway having one of its sides movable to and from the other to vary the width of the runway, of an inclined fender located at the terminus of the runway beyond the opening through which the coins drop from the runway, 105 guides in which the fender is supported and can slide crosswise of the runway, and a spring by which the head of the fender is held with yielding pressure against the adjustable side of the runway, whereby the 110 fender automatically adapts itself to the movements of said adjustable side, substantially as hereinbefore set forth.

8. In a coin counting machine, the combination with the runway and means for 115 conveying coin therethrough, and the star wheel having a determined number of teeth which project one at a time into the runway in position to be struck and moved by the passing coins so as to revolve the star wheel. 120 of the rotatable ratchet wheel; an actuating pin or finger on the star wheel arranged and operating to engage and move the ratchet wheel a distance of one tooth at each revolution of the star wheel; a setting disk 125 to determine the extent of rotary movement of the ratchet wheel, said disk being rotatable to vary the extent of that movement; a spring t which tends to revolve the ratchet wheel in a direction opposite to that in 130

which it is revolved by the star wheel; the pivoted spring pressed pawl lever p ; the stop n^{10} on the star wheel; the stop arm p^s on the pawl lever; and dogs at determined points upon the interior opposite faces of the setting disk and ratchet wheel to limit the back revolution of the ratchet when released from the pawl, substantially as and for the purposes hereinbefore set forth.

9. In a machine of the class described, the combination of the runway; the star wheel n ; the rotatable ratchet wheel o having peripheral recess o^2 of greater depth than the ratchet teeth; the rotatable setting disk r and means for securing it in adjusted position; the dogs $o' r^4$ on the interior opposite faces of the ratchet wheel and setting disk; a ratchet wheel-actuating pin n^9 on the star wheel; the pivoted spring-pressed pawl lever p ; the spring t for imparting back revolution to the ratchet wheel when the latter is released from its pawl lever; the stop n^{10} on the star wheel; and the stop arm p^s on the pawl lever—these parts being combined to operate jointly substantially in the man-

ner and for the purposes hereinbefore set forth.

10. The combination substantially as set forth of the rotatable setting disk r having on its under face a dog r^4 ; means for securing the setting disk in adjusted position; the ratchet wheel o having on its upper face a dog o' , and, diametrically opposite dog o' , in its periphery a recess o^2 of dimensions to permit the actuating pin n^9 of the star wheel n to move therein without engaging the ratchet wheel; a spring t tending to impart movement of back revolution to the ratchet wheel; a spring-pressed pawl p for holding the ratchet wheel against the stress of spring t ; the star wheel n and pin n^9 thereon; a register n^8 ; and gearing whereby the movement of the star wheel is caused to actuate the register.

In testimony whereof I affix my signature in presence of two witnesses:

HERBERT K. SMITH.
